REMOVABLE COOKING PAN-LID HOLDING CLIP

Daniel L. Reedy, Selby, S. Dak.

Application October 7, 1955, Serial No. 38,297

Term of patent 14 years

(Cl. D17—3)

Fig. 1 is a front perspective view of a removable cooking pan-lid holding clip, showing my new design;
Fig. 2 is a rear perspective view thereof; and
Fig. 3 is a top plan view thereof.

I claim:

The ornamental design for removable cooking pan-lid holding clip, substantially as shown.
